MAGNETIC SWEEPER

Charles W. Ross, 1831 14th St., Moline, Ill.
Filed Sept. 16, 1960, Ser. No. 56,430
9 Claims. (Cl. 209—215)

This invention relates to a mobile magnetic sweeper adapted to move over a surface and to pick up ferrous materials.

In the magnetic sweeper art it has heretofore been conventional to construct the sweeper with a mobile frame carrying a permanent magnet and associated pole plates. A panel of non-magnetic material is disposed between the pole plates and surfaces to be swept so that ferrous particles impinge against the plate. Customarily provision is made to remove the magnet and pole plates away from the panel or plate to relieve the magnetic attraction so that the ferrous materials will gravitate from the plate and either be collected or scrapped as desired. Generally the main frame carrying the magnet and pole plates is pivotally mounted relative to the non-magnetic panel or plate and separation of the magnetic field and nonmagnetic plate is done simply by swinging or pivoting one away from the other.

It is the primary object of the present invention to provide a magnetic sweeper of a new and novel design in which all parts of the sweeper are rigidly joined together by a simple means but may be dismantled for inspection or maintenance work.

Specifically it is the object of the present invention to provide a magnetic sweeper featuring a downwardly opening mobile casing of magnetic material and closed at its underside by a non-magnetic plate which extends outwardly beyond the vertical walls of the casing to outer upwardly inclined portions. Contained within the casing is a permanent magnet structure which operates as the casing is moved over a floor or surface to cause ferrous particles to impinge against the under surface of the under plate. However, due to the nature of the magnet, the flux lines created thereby will be shorted or will not penetrate through the magnetic walls of the casing. Consequently, the magnetically attracted ferrous particles may be wiped by a cloth along the under surface of the underplate and upon their reaching the outer portions of the underplate, or that portion outwardly of the confines of the casing, the magnetic attraction will be reduced to a point in which they will gravitate from the respective outer portion of the underplate.

Other objects and advantages of the invention will become apparent to those skilled in the art as the nature of the invention is better understood from the following description and as shown in the accompanying drawings.

FIGURE 1 is a side perspective view of the magnetic sweeper incorporating the structure of the present invention.

FIGURE 2 is a vertical sectional view along the fore and aft center line of the sweeper.

FIGURE 3 is a sectional view taken substantially along the lines 3—3 of FIGURE 2.

Referring to the drawings, the sweeper has a housing structure including a box-like downwardly opening casing 10. The casing includes a top or overhead panel 11, front and rear upright side walls 12, 13 respectively and transversely spaced upright side walls 14, 15. The entire casing 10 is of a one-piece construction and is composed of magnetic or ferrous material.

Closing the open underside of the box structure 10 is an underplate 16 which extends between and abuts the lower edges of the side walls 12, 13, 14, and 15, and has a forward upwardly inclined lip portion 17 projecting forwardly of the front wall 12 and a rearward upwardly inclined

2

lip portion 18 projecting rearwardly from the rear wall 13. The fact that the lips 17, 18 are inclined is important since it places them outwardly of the walls 12, 13. Also important is the fact that the underwall 16 is composed of a non-magnetic material, a high grade stainless steel being the preferred type used.

A pair of wheels 20, 21 are supported on the housing structure side walls 14, 15 by means of studs 22, 23 threaded on their internal ends. The threaded ends extend through suitable openings in the side walls 14, 15 and are held rigid thereon by means of nuts 24, 25 and 26, 27 which are tightened against opposite sides of the walls 14, 15, lock washers as at 28, 29 being provided between the nuts 25, 27 and the respective walls 14, 15. The wheels 20, 21 are rotatably carried on smooth outer ends of the studs 22, 23 and are held thereon by means of cotter pins 30, 31. Washers 32, 33 and 34, 35 are provided on opposite sides of the wheels 20, 21 so as to maintain a relatively free rotation of the wheels.

A magnetic field is maintained for the sweeper by a semi-circular permanent magnet 40. The magnet 40 is of a cast alloy material and may be of any of several horseshoe type magnets commercially produced. The magnet 40 creates opposite north and south poles shown as N and S respectively on the drawings. The magnet 40 is centrally located between the side walls 14, 15 and has the lower ends of its leg portions abutting against the upper surface of laterally disposed pole plates 41, 42. The pole plates 41, 42 are of a magnetic composition and consequently the magnetic field is spread the length of the plates. The proximate edges of the pole plates 41, 42 are spaced from the housing walls 12—15.

Brass bolts 45, 46 extend through the pole plates 41, 42, suitable countersunk openings 47, 48 being provided on the under side of the plates 41, 42 to receive the heads of the bolts. The shank of the bolts 45, 46 extends through vertical openings or holes 49, 50 in the front and rear portions of the horseshoe magnet 40. The upper ends of the bolts are threaded and nuts 51, 52 are provided to fix the magnet in position and in engagement with the pole plates 41, 42.

The upper ends of the brass bolts 45, 46 have upper threaded portions extending through the overhead plate 11 of the casing 10. An upwardly inclined handle 55 extends from the housing structure 10 and has a lower horizontally disposed and fore and aft extending portion 55a lying adjacent the upper surface of the overhead plate 11. The upper ends of the bolts 45, 46 extend through the handle portion 55a. Nuts 56, 57 are threaded on the bolts 45, 46 above the handle portion 55a. The pole plates 41, 42 are spot welded to the underplate 16. Consequently, by tightening the nuts 56, 57 on the bolts 45, 46, the handle becomes rigidly united with the housing structure 10. Also, the lower edges of the upright walls 11—15 closely engage the surface of the under panel and are rigidly held against separation. If it is desired to take the unit apart, such may be done merely by removing the nuts 56, 57 at which time the handle 55 may be removed and the housing structure or casing 10 removed to expose the magnet structure.

The sweeper operates in the following manner. Normally it is manually pushed or pulled over the floor. Ferrous articles will be attracted by the magnet structure 40, 41, 42. However, the flux of the magnet system will not penetrate in any sizable strength beyond the front and rear side walls 12, 13. Consequently, the ferrous articles will impinge against and be held against the bottom of the plate 16 and the portion of the plate 16 within the confines of the walls 12, 13.

In order to remove the ferrous articles from the plate 16, the entire unit may be raised or turned over and the articles may be wiped by a cloth or other suitable means

to either of the lips 17, 18 at which location the magnetic effect of the magnet structure 40, 41, 42 is of negligible amount and the lips 17 and 18 may be wiped clean with little effort.

In moving over the floor, the sweeper may encounter bolts, boards, and other such projecting objects of height greater than the lower surface of the underplate 16. By providing lips or portions 17, 18, the sweeper may be guided over them even though the wheels may be momentarily raised off the floor. If the objects are of magnetic substance, they will adhere to the plate 16 and the plate will need to be wiped prior to further sweeping. Also, when approaching large machine tools with framework bolted or otherwise fixed to the floor, the inclined portions 17, 18 will tend to guide the plate 16 over the lower flanges of the framework (which normally rest on the floor) until the wheels contact the flanges. Consequently, even the small ferrous particles which normally avoid being picked up by other sweepers may be picked up with the present sweeper.

While only one form of the invention has been shown, it should be recognized that other forms and variations will occur to those skilled in the art. Therefore, while the present form was shown and described in detail for the purpose of clearly and concisely illustrating the principles of the invention, it was not the intention to limit or narrow the invention beyond the broad concept set forth in the appended claims.

What is claimed is:

1. A magnetic sweeper comprising: a metallic casing of magnetic material opening downwardly and having oppositely disposed transversely spaced upright side walls, fore and aft spaced upright side walls and an overhead wall interconnecting the upper edges of the aforesaid walls; wheel structure effecting mobility of the casing fixed to and extending outwardly from the side walls; a laterally disposed underplate of non-magnetic material disposed beneath and normally abutting the lower edges of the walls, said plate having upwardly inclined end portions extending laterally beyond the lower edges of the walls; a permanent magnet disposed within the casing having opposite ends defining opposite poles and having upright openings therein; a pair of parallel laterally disposed pole plates fixed to the upper surface of the underplate; non-magnetic studs mounted on the pole plates and extending upwardly through the openings in the permanent magnet and through the overhead wall to upwardly projecting ends; means associated with the studs for mounting the magnet in engagement with the pole plates and against movement relative to the studs; and an elongated rigid control element having a lower end mounted on the upwardly projecting ends of the studs and an upper remote end adapted for manual manipulation.

2. A magnetic sweeper comprising: a metallic casing of magnetic material opening downwardly and having oppositely disposed transversely spaced upright side walls, fore and aft spaced upright side walls and an overhead wall interconnecting the upper edges of the aforesaid walls; wheel structure effecting mobility of the casing fixed to and extending outwardly from the side walls; a laterally disposed underplate of non-magnetic material disposed beneath and normally abutting the lower edges of the walls, said plate having upwardly inclined end portions extending laterally beyond the lower edges of the walls; a permanent magnet disposed within the casing having opposite ends defining opposite poles and having upright openings therein; a pair of parallel laterally disposed pole plates fixed to the upper surface of the underplate; non-magnetic threaded studs mounted on the pole plates and extending upwardly through the openings in the permanent magnet and through the overhead wall to upwardly projecting ends; nuts threadedly associated with the studs for bearing downwardly against the magnet to effect engagement with the pole plates; and an elongated rigid control element having a lower end mounted on the

upwardly projecting ends of the studs and an upper remote end adapted for manual manipulation.

3. A magnetic sweeper comprising: a metallic mobile casing of magnetic material opening downwardly and having transversely spaced upright side walls, front and rear upright side walls and an overhead wall interconnecting the upper edges of the aforesaid walls; transversely spaced wheels effecting mobility of the casing mounted on and extending outwardly from the side walls; a laterally disposed underplate of non-magnetic material disposed beneath and normally abutting the lower edges of the walls, said plate having upwardly inclined front and rear end portions extending laterally beyond the lower edges of the front and rear side walls; a permanent magnet disposed within the casing having opposite ends defining opposite poles and having upright openings therein; a pair of parallel and transversely disposed lateral pole plates fixed to the upper surface of the underplate in spaced relation to one another; non-magnetic studs mounted on the pole plates and extending upwardly through the openings in the permanent magnet and through the overhead wall to upwardly projecting ends; means associated with the studs for mounting the magnet in magnetic engagement with the pole plates; and an elongated rigid control element having a laterally disposed lower end mounted on the upwardly projecting ends of the studs and inclined to an upper remote end adapted for manual manipulation.

4. A magnetic sweeper comprising: a mobile casing opening downwardly and having vertically disposed side walls of magnetic material; a laterally disposed underplate of non-magnetic material disposed beneath and normally abutting the lower edges of the side walls, said plate having at least one upwardly inclined portion extending laterally beyond the lower edges of the side walls; a permanent magnet disposed within the casing having opposite ends defining opposite poles and having upright openings therein; a pair of parallel and transversely disposed lateral pole plates fixed to the upper surface of the underplate in spaced relation to one another; non-magnetic studs mounted on the pole plates and extending upwardly through the openings in the permanent magnet to upwardly projecting ends; and an elongated control element having a lower end mounted on the upwardly projecting ends of the studs and inclined to an upper remote end.

5. A magnetic sweeper comprising: a casing opening downwardly having upright side walls composed of magnetic material and an overhead wall interconnecting the upper edges of the side walls; wheel structure effecting mobility of and mounted on the casing; a laterally disposed underplate of non-magnetic material disposed beneath and normally abutting the lower edges of the walls, said plate having at least one upwardly inclined end portion extending laterally beyond the lower edges; a magnet structure disposed within the casing having opposite poles with upright openings therein; non-magnetic studs rigid with the underplate and extending upwardly through the openings in the magnet structure and through the overhead wall to upwardly projecting ends; and an elongated control lever means having a lower end mounted on the upwardly projecting ends of the studs and an upper remote end.

6. A magnetic sweeper comprising: a mobile casing opening downwardly having vertically disposed side walls composed of magnetic material; a laterally disposed underplate of non-magnetic material disposed beneath the lower edges of the walls, said plate having at least one upwardly inclined portion extending laterally beyond and outside the confines of the side walls; a magnet structure supported within the casing; and an elongated control lever means having a lower end connected to the casing and extending to an upper free end remote from the casing.

7. A magnetic sweeper comprising: a mobile casing opening downwardly having vertically disposed side walls

composed of magnetic material; a laterally disposed underplate of non-magnetic material disposed beneath the lower edges of the walls, said plate having at least one portion extending laterally beyond and outside the confines of the side walls; a magnet structure supported within the casing; and an elongated control lever means having a lower end connected to the casing and extending to an upper free end remote from the casing.

8. The invention defined in claim 7 in which the casing has a front and rear side wall and the underplate extends beyond the lower edge of the front wall to define said portion of the underplate, and said portion is inclined upwardly in respect to the lower edge of the front wall.

9. The invention defined in claim 7 in which the casing has a front and rear side wall and the underplate has a portion thereof extending forward of the front wall and a portion extending rearward of the rear wall and both of said portions are inclined upwardly in respect to the respective lower edges of the front and rear side walls.
